Philips Xenium X830, announced Jul. 2009, [online], [retrieved on Aug. 6, 2009]. Retrieved from Internet ,<URL: <http://www.gsmarena.com>>.*Primary Examiner — Bridget L Eland*(74) Attorney, Agent, or Firm* — Steven M. Reiss(57) **CLAIM**

The ornamental design for a mobile phone, as shown and described.

DESCRIPTION

FIG. 1 is a perspective view of a mobile phone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines immediately adjacent the claimed areas represent the bounds of the claimed design while all other broken lines are directed to environment and are for illustrative purposes only; the broken lines form no part of the claimed design.
